[57] **ABSTRACT**

Ink distributing means for a printing press comprising a bundle of rollers, each contacting two other rollers. The axes of said rollers are displaced to form a twisted bundle. The surfaces of two of the rollers are elastic to accommodate the displacements of the axes and make good contact along the lengths of said rollers.

FIG 1

FIG 2A

INVENTOR.
HENRY HARRISON
BY

**INK DISTRIBUTING MEANS COMPRISING A
BUNDLE OF SKEWED ROLLERS**

This invention relates to ink distributing roller means. More particularly, the invention provides new and improved ink distributing roller means which eliminate the need for axially moving one or more of the ink feed rollers.

It is common practice in printing machines to provide at least one roller in the train of ink rollers, which reciprocates in an axial direction while it turns. This roller, commonly called the vibratory roller or vibrator, maintains a uniform or graded thickness of ink across the lateral dimension of the press. Without a vibrator, the ink distribution becomes thin in bands where image areas deplete it and becomes thick in the non-image areas. The boundaries between thick and thin areas become sharply defined, resulting in very noticeable variations of density in the printed image. This is sometimes called "ghosting."

Various means have been employed to impart axial vibratory motion and rotary motion simultaneously to a vibrator roller. All are intermittent in operation, introducing undesired dynamic forces and reduced efficiency of operation. All are mechanically complex, requiring a cam or crank driving device and special bearings. These mechanisms, introduce cost and wear problems.

Accordingly, it is a primary object of this invention to provide a roller means for distributing ink laterally in a continuous fashion employing rotary motion only, without axial reciprocation or rotation. By this simplification the cost of a machine will be significantly reduced and the efficiency of uniforming the ink will be improved.

Another object of the invention is to provide new and improved ink feeding means for printing presses.

Another object of the invention is to provide new and improved ink feeding means for printing presses comprising a bundle of feed rollers, at least four in number, each roller contacting two other rollers, the axes of said rollers being displaced to form a twisted bundle.

These and other objects of the invention will be apparent from the following specification and drawings of which:

FIG. 1 is a perspective view of an embodiment of the invention.

FIG. 2 is an enlarged perspective view of the twisted bundle of rollers illustrating the operation of the invention.

FIG. 2A is an end view of FIG. 2.

FIG. 1 shows a typical arrangement of ink rollers. Ink is transferred from the slow-turning ink fountain roller 11 to the ductor roller 12, which intermittently touches a hard-surfaced idler roller A, turning at press speed. This hard surface idler A makes contact with a pair of elastic-surfaced rollers B and C which convey ink to a hard surfaced distributor roller D geared to turn at press speed. This distributor D roller drives the idler roller system. From the distributor roller two idling elastic-surfaced form rollers E and F transfer ink to the surface of the type or plate roller G image areas, and from there it goes to the surface being printed directly, in letterpress machines, or via an offset blanket in offset machines. Rollers B and C are skewed in the same direction with respect to roller A. Roller D is addi-

tionally skewed in the same direction with respect to rollers B and C. Rollers A, B, C and D comprise a "twisted bundle."

In conventional printing machines either the hard-surfaced idler roller A or the distributor roller D or both would have reciprocating axial motion as well as rotation, to smooth irregularities of ink thickness across the width of the roller system.

In the present invention, both the hard surface distributor D and the hard surface idler A, and also the two elastic-surfaced rollers B and C between them, rotate without axial motion, at press speed in constant contact with each other, but the axes of the four rollers are not parallel to each other.

How this roller system works to smooth irregularities of ink thickness across the width of the roller system can be understood from FIG. 2.

Suppose an irregularity in the ink film thickness on roller A exists in the first zone. This irregularity comes in contact with roller B at contact point 1, with roller C at point 2, with roller C at point 3, and again with roller A at point 4. But point 4 is in a second zone, displaced from the first zone where the irregularity was first assumed to be. Thus the ink film thickness in the first zone is averaged with the thickness in the second zone. At the same time, an irregularity in zone 2 would travel to a third zone or beyond it and so on over the whole width of the roller system.

An exchange process where an irregularity passes from contact 1 to contact 2 to contact 3 to contact 4 has been described. Without reversing the rotation of the rollers, a reverse exchange also takes place, bringing an irregularity at contact 4 around the outside of roller D to contact 3, around the inside of roller C to contact 2, around the outside of roller B to contact 1. Thus an irregularity in zone 1 continuously exchanges or averages not only with zone 2 but also with another zone on the opposite side of zone 1.

Theoretically all these rollers should be hyperboloids of one sheet, but in practice the angle between axes of rotation is so small that cylindrical elastic-surface rollers easily compress to make good contact over their entire length. An angle of about 2° between successive axes has been found to give good results. The number of rollers in the twisted group exchanging can be any even number greater than or equal to four. The "hand" of the twist of the roller axes or of rotation of the distributor roller, for example, have no effect on the exchange process, which takes place equally in both directions. The angle of twist determines the distance between exchange zones on any particular roller, which is related to the rate at which a lateral unevenness of the ink film is averaged out.

FIG. 2A shows an end view of FIG. 2.

The invention is not limited to printing presses, but has application wherein a liquid is being fed by rollers, for instance in chemical processing machines.

Uniforming action takes place whenever the rollers contact each other in a complete sequence. In cases where constant uniforming action is not required, one of the chain of rollers may be a ductor making intermittent contact. Lateral irregularities in the ink film which develop while the ductor is in contact with the fountain roller are smoothed out while the ductor is in contact with distributor rollers, completing the twisted bundle.

Similarly, where a bare minimum number of ink rollers is a primary consideration, a form roller may be included in the twisted group of rollers.

I claim:

1. A roller system for distributing a viscous material including an input roller means for supplying ink to said input roller, two intermediate rollers and an output roller, each intermediate roller being mounted in rolling contact with said input and output rollers, means fixing the axis of each intermediate roller in a skewed position with respect to the input roller, and means locating the axis of the output roller in a skewed direction with respect to said intermediate rollers, said

4
direction of skew being the same as the axis of each of said intermediate rollers, whereby an irregularity in ink film thickness on said input roller is averaged along its length.

5 2. Apparatus as in claim 1 wherein the axes of contacting rollers are displaced, 2°.

3. Apparatus as in claim 1 wherein said input and output rollers of said four rollers have a harder surface than said intermediate rollers, and said intermediate rollers have elastic surfaces to provide continuous contact along their length.
